UNITED STATES PATENT OFFICE.

ADDISON W. HITT, OF ST. LOUIS, MISSOURI, ASSIGNOR OF ONE-HALF TO
HENRY C. KING, OF CHARLESTON, SOUTH CAROLINA.

SYRINGE.

SPECIFICATION forming part of Letters Patent No. 468,620, dated February 9, 1892.
Application filed September 18, 1891. Serial No. 406,124. (No model.)

To all whom it may concern:

Be it known that I, ADDISON W. HITT, a citizen of the United States, residing at St. Louis, in the State of Missouri, have invented 5 a new and useful Syringe, of which the following is a specification.

This invention relates to vaginal syringes; and it has for its object to provide an instrument for the purpose of washing or medically 10 treating the vagina which will be simple in construction and one which may be used with facility and ease; also, to provide a syringe having means whereby the walls of the vagina may be dilated for the usual purpose to insure 15 a thorough washing or injection from the injected fluid.

With these and other objects in view the invention consists of a syringe-nozzle and a guard or shield carrying radially-hinged arms 20 operated by a reciprocating movement of said nozzle and constructed and arranged in the novel manner hereinafter more fully described, illustrated, and claimed.

In the accompanying drawings, Figure 1 is 25 a perspective view of a vaginal syringe constructed in accordance with my invention, the arms being expanded. Fig. 2 is a vertical longitudinal section of the same, the arms being collapsed. Fig. 3 is a vertical transverse 30 section, the arms being expanded. Fig. 4 is a similar view of a modification. Fig. 5 is a detail view illustrating the locking-slot.

Referring to the drawings, 1 designates a shield or guard, the same being constructed 35 of hard rubber or other suitable material that will not be affected or corroded by the liquids which come in contact with it. The said shield or guard is elliptical in shape and adapted to bear upon and rest upon the labia, 40 preventing the escape of the washings except from directly beneath the vagina, and the shield is provided with a central perforation 2, from which extends the depending tubular neck 3, having near its lower edge the closed 45 bayonet-slot 4, the purpose of which will be soon apparent.

A series of spaced lugs or elevations 5 project above the face of the shield and are arranged around the central perforation there- 50 in. The said lugs are provided with the per-

forations 4^a and are beveled upon their inner edges, as at 6, in order to accommodate the ends of the expanding arms 7 and the operating nozzle. The arrangement of the inner beveled lugs also provides a back reservoir, from 55 which the fluids escape through the communicating discharge-perforation 8, which perforation extends through the tubular neck 3 and receives in its lower end the discharge-nozzle 9. The said discharge-nozzle by suitable tubing 60 conducts the discharge to any convenient receptacle. The expanding arms 7 are each provided with the lower flared ends 10, terminating in the reduced portions 11, which are hinged to the top of the shield or 65 guard by means of the pins 12 passing therethrough and the perforations in said lugs, between which the ends of said arms are placed. Two of the expanding arms 7 are of a rounded 70 sector shape, and when collapsed together form a semicircular portion, the circle of which is completed by the remaining hinged arm approximately semicircular and provided with the flat face 13, which is adapted to register with the inner flat faces 14 of each of 75 the sector-arms, thus completing, when collapsed, a tapering rounded dilator flared at its base and providing for a ready and easy insertion within the vagina, and which when within the same may be easily expanded, as 80 described. The meeting faces of the opposing sector-arms are each provided with the longitudinal rounded grooves or recesses 15, while each of said arms are further provided with the lateral notches 16 at their lower 85 inner edges and the inwardly-projecting ends 17, extending from said notches at right angles to the arms and having the inner curved edges 18, which, when the arms are collapsed or closed, form a curve within which the nozzle-tube 19 is located. Said nozzle-tube 19 extends through the tubular depending neck of said shield and is provided at its lower end with an ordinary shouldered end 20, over 90 which may be placed ordinary tubing connecting the nozzle-tube with a suitable syringe for the purpose. The upper end of said nozzle-tube 19 terminates in a reduced nozzle 21, having the perforations 22 and provided with the exteriorly-threaded portion 100

23, that is designed to accommodate the annular flange or disk 24, screwing thereover and upon the shoulder 25 at the upper end of the nozzle-tube from which the nozzle arises.

5 When the dilator is collapsed, the reduced nozzle is designed to snugly fit within the longitudinal grooves 15 in said arms, and thus be entirely inclosed within the rounded sectional dilator during insertion, while said annular flange is adapted to take within the lateral notches 16 in each arm and rest within the inclosed space above the shield-perforation. It can be readily seen that after the instrument is inserted within the vagina that by pressing the nozzle-tube upward the pressure of the annular flange upon the upper side of said receiving-notches will cause the dilator to expand and the arms thereof to dilate the walls of the vagina while the fluid is injected within the same. A downward pull of said nozzle-tube bears the flange upon the inwardly-projecting ends of the arms and tightly closes the same in upon the tube and nozzle, as set forth. The instrument is held in its dilated and closed positions by means of the set-screw 26, screwed into said nozzle-tube and working within the closed bayonet-slot 4 in the tubular neck, so in operating the tube it is slightly turned and forced upward or downward to dilate or collapse.

30 A modification of the manner of hinging the dilator-arms to the perforated lugs upon said shield appears in the drawings, and is designed for the purpose of greater strength and durability. The lower ends of the arms are provided with the slots 7^a, within which are inserted the metal angle-pieces 7^b, which are flush with the extreme lower ends of the arms and extend forward, as at 7^c, beneath said ends beyond the points of the pivot, so as to form corresponding lateral notches 16 and the inwardly-projecting ends 17, as described. The nozzle-tube and flange work in the same manner within said angle-pieces.

45 The construction and operation of my improved vaginal syringe is thought to be apparent without further description.

Having thus described my invention, what I claim, and desire to secure by Letters Patent, is—

50 1. In a vaginal syringe, a shield having a central perforation, a series of dilating arms hinged upon said shield and having registering faces provided with longitudinal grooves, and a reciprocating nozzle projecting through said central perforation and connected with and operating said arms and adapted to be

entirely inclosed within the grooves in the same when collapsed, substantially as set forth.

60 2. In a vaginal syringe, an elliptical shield having a central depending tubular neck, a series of radial spaced lugs upon said shield, registering and rounded dilating arms hinged between said lugs and provided with inner 65 notches, and a reciprocating nozzle working within said neck and provided with an annular flange adapted to engage said inner notches, substantially as set forth.

70 3. In a vaginal syringe, a shield having a central perforation, a series of rounded dilating arms having flat registering faces hinged to said shield and provided with longitudinal rounded grooves upon their meeting faces, lateral notches and inwardly-projecting ends 75 at their lower extremities, a reciprocating nozzle-tube having a reduced nozzle end adapted to be inclosed within the longitudinal grooves of said arms, and an annular flange or disk secured upon said nozzle-tube and adapted 80 to engage said lateral notches and inwardly-projecting ends, substantially as set forth.

4. In a vaginal syringe, a shield having a depending tubular neck provided with a closed bayonet-slot at its lower end, a series 85 of dilating arms hinged to said shield, and a reciprocating nozzle working within said neck and provided with a set-screw engaging said slot and connected with said arms, substantially as set forth.

90 5. In a vaginal syringe, a shield having a central perforation and a tubular neck depending therefrom, spaced lugs having inner curved beveled edges upon said shield around the perforation therein, a discharge-spout 95 communicating with the space inclosed by said lugs laterally through said neck, a series of dilating arms hinged between said lugs and provided with lateral notches, inwardly-projecting ends having curved edges and registering longitudinal grooves, and a reciprocating nozzle working within said neck and provided with an annular flange adapted to engage said notches and ends, said nozzle being adapted to be inclosed within said arms, 100 substantially as set forth.

105 In testimony that I claim the foregoing as my own I have hereto affixed my signature in the presence of two witnesses.

ADDISON W. HITT.
